CLAIM

The ornamental design for a multiple panel reflector dish antenna, as shown and described.

DESCRIPTION

FIG. 1 is a front isometric view of a multiple panel reflector dish antenna in accordance with the present invention.

FIG. 2 is a back isometric view of the multiple panel reflector dish antenna of FIG. 1.

FIG. 3 is a front view thereof.

FIG. 4 is a back view thereof.

FIG. 5 is a side view thereof (both right and left side views are identical).

FIG. 6 is a top view thereof; and,

FIG. 7 is a bottom view thereof.

The broken lines shown in FIGS. 1-7 represent portions of the multiple-panel reflector dish antenna that form no part of the claimed design.

1 Claim, 7 Drawing Sheets
